LUBRICATING MEANS FOR PUMPS

Edgar E. Greve, Bellevue, Pa., assignor, by mesne assignments, to Oil Well Supply Company, of Pittsburgh, Pa., a Corporation of New Jersey

Application February 13, 1929. Serial No. 339,624

2 Claims. (Cl. 184—13)

This invention relates to improvements in means for lubricating the working parts of the power end of a pump or similar apparatus, and it is particularly directed to means for conveying or circulating the lubricant, said means associated with the gear drive mechanism of the pump or the like.

The usual gear mechanism employed in devices of the character of the present invention includes a plurality of drive pinions disposed above two relatively large gear wheels.

In some instances, attempts have been made to lubricate the working parts of the pump by running the large gear wheels in a lubricant contained in a reservoir of the pump casing, and passing the lubricant from the large gear wheels to the pinions, and from thence to other parts of the pump, for the purpose of lubricating the gear mechanism and the other parts. This method, however, has not proven successful, due to the inability of carrying the desired quantity of lubricant to the pinions and to the lack of means for directing what lubricant was supplied to the said pinions to the other working parts.

It is a prime object of this invention to provide a means for applying the lubricant to the gear mechanism whereby it is conveyed by the teeth of one gear to the point of contact with another gear or pinion, squeezing or jetting the lubricant outwardly from between said gears against a baffle plate and onto troughs by which it is conveyed to other working parts of the machine.

Further objects are to provide a construction which may be easily adapted to an apparatus of this character, to maintain an uninterrupted flow of lubricant throughout the pump, and to provide a simple and inexpensive construction.

In the drawing, which shows a preferred embodiment of my invention:

Fig. 1 is a plan view, partly broken away, showing my invention applied to the power end of a belt-driven pump; and

Fig. 2 is a vertical sectional view taken on the line II—II of Fig. 1.

Referring to the drawing, 5 designates a casting or housing of the power mechanism of a pump. Extending transversely thereof is a drive shaft 6, adapted to be driven by a pulley 7 from a source of power, not shown.

Drive shaft 6 is provided with pinions 8 integral therewith or keyed to the shaft, said pinions being in operative engagement with relatively large gear wheels 9 carried on a crank shaft 10. Crank shaft 10 is mounted in a cen-

tral bearing 11 and end bearings 12 secured to the housing 5. 13 designates connecting rods mounted on the crank pins 14, said pins being integral with gear wheels 9. The other ends of connecting rods 13 are secured to cross-heads 15 by means of cross-head pins 16. Cross-heads 15 slide in guides 17, imparting a reciprocating motion to the piston rods 18, as will be readily understood.

The housing 5 is formed with a lubricant-receiving portion or reservoir 19, which is designed to contain the desired quantity of lubricant, designated *a*, which may be a heavy cylinder oil. Positioned within the reservoir 19, and around the lower portion of the peripheries of gear wheels 9, I provide semi-circular troughs 20, secured to the housing in any suitable manner.

Bolted or otherwise secured to a vertical rib 21 of the housing 5, are pans or troughs 22, the free ends of which rest on a wall 23 of said housing. A vertical plate or baffle 24 is positioned between the troughs 22 and bolted to the rib 21 in the manner shown.

Troughs 22 and the baffle 24 are positioned midway between the pinions 8 and gear wheels 9, and in the path of the lines of contact of said gears. The lubricant in the reservoir 19 will be carried upwardly in the troughs 20 by the rotation of gear wheels 9. These troughs extend around the periphery of the gear wheels for a sufficient distance and function to cause a suitable amount of the lubricant to remain in the gear teeth after having emerged from the troughs. When the lubricant comes into contact with pinions 8, it will be squeezed or jetted laterally. The lubricant jetted inwardly will strike baffle 24 and be deflected into the troughs 22. That which is jetted outwardly will serve to lubricate the bearings 6a of the drive shaft.

The lubricant will flow from the troughs 22 onto the wall 23, where it is distributed to the other working parts by means of communicating passages. Thus, openings *b* will lubricate the connecting rods 13, pins 14, cross-head pins 16, by means of communicating passages. Also, by means of opening *c*, the cross-heads 15 and their slides 17 are lubricated; and by means of openings *d*, lubrication is applied to the piston rods 18 and their glands 25.

Thus, it is seen a continuous and uninterrupted flow of lubricant is obtained which will adequately lubricate the working parts.

Various changes and additions are contemplated, provided they fall within the scope of the following claims.

I claim:

1. The combination with a pump casing having a lubricant reservoir disposed therein, a pair of spaced apart curved troughs associated with 5 the reservoir and communicating therewith, a gear mechanism within the casing including a pair of gears each operable within a trough, and a pair of pinions mounted above the liquid level and meshing with the gears, and means associated 10 with the pinions for catching and passing lubricant discharged from the gears and pinions to other working parts of the pump including a baffle plate located intermediate of the gears, and centrally disposed troughs disposed below 15 said pinions.

2. The combination in a pump of a pump casing having a lubricant reservoir disposed therein, gear mechanism within the casing including a pair of gears having a path of travel below the liquid level of the reservoir and a pair of pinions mounted above the liquid level and meshing with the gears, and means associated with the pinions for catching and passing lubricant discharged from the gears and pinions to other working parts of the pump, said means being disposed intermediate and below said pinions. 80 85
